UNITED STATES PATENT OFFICE.

WILLIAM T. McCUE, OF PITTSBURGH, PENNSYLVANIA, ASSIGNOR TO PATRICK WALL,
OF PITTSBURGH, PENNSYLVANIA.

ICE-CAN.

1,128,162.

Specification of Letters Patent.

Patented Feb. 9, 1915.

Application filed August 12, 1913. Serial No. 784,381.

To all whom it may concern:

Be it known that I, WILLIAM T. McCUE, a subject of the King of England, residing at Pittsburgh, in the county of Allegheny 5 and State of Pennsylvania, have invented a new and useful Ice-Can (Case A,) of which the following is a specification.

This invention relates to cans of that type used in the manufacture of ice, and also relates to a method of producing the same.

Heretofore, in constructing a can of this character, the walls have been first shaped and secured together after which the corners have been cut away at the bottom. The bottom edge portions of the walls have then been folded upwardly between the cuts to form channels designed to receive depending flanges on the bottom of the can. Rivets have then been secured in the interfitting 15 portions of the bottom and walls so as to hold them together and prevent leaking.

In practice it has been found that an ice can, when subjected to the usual rough handling, receives its greatest strains at its bottom corners, this being due to the fact that in dropping the heavy cans, they usually hit at their corners upon the floor. It has developed, furthermore, that in cans such as herein described, the formation of 20 corner cuts to permit folding of the bottom portions of the can walls, has greatly weakened the corners and, as a result, these corners soon break open and the cans are therefore rendered unfit for further use in 25 the manufacture of ice.

One of the objects of the present invention is to provide an improved can structure in which the bottom corner portions of the can walls are retained, instead of cut 30 away, and are utilized as reinforcing means whereby inward bending of the corners of the can is practically prevented and the life of the can consequently prolonged.

A further object is to provide a can structure in which the bottom corner portions of the wall are retained instead of cut away so as thus to provide a continuous channel whereby the solder floated into the seam or channel between the can walls and the bottom is retained and will not drain therefrom as heretofore.

A further object is to provide a can, the bottom of which is formed with a continuous uninterrupted flange designed to engage 35 the folds of the walls and thus not only

form a tight joint but also act as a tie to hold the can walls together at the seams and prevent distortion of the can.

With the foregoing and other objects in view the invention consists in certain novel 40 steps in the method of producing the can and in certain novel details of construction hereinafter described and claimed, it being understood that changes in the precise embodiment of the invention herein disclosed, 45 can be made within the scope of what is claimed, without departing from the spirit of the invention.

In the accompanying drawings the preferred form of the invention has been 50 shown.

In said drawings:—Figure 1 is a perspective view of the can. Fig. 2 is a perspective view of a portion of the bottom of the can inverted and showing the reinforcing rib 55 or fold in one corner thereof. Fig. 3 is a perspective view of the outer side of one corner portion of the can. Fig. 4 is a perspective view of the inner side of one corner portion of the can, the bottom being removed and a portion of one side of one of the plates used in producing the walls of the can being also shown. Fig. 5 is a perspective view of a portion of one side of one 60 of the plates used in the formation of the can and which is adapted to lap the edge portion shown in Fig. 4. Fig. 6 is a detail view of one end portion of the blank from which certain of the walls of the can are 65 formed. Fig. 7 is a perspective view of a portion of the blank and showing one of the ribs struck from the blank prior to folding the bottom edge portion of the blank. Fig. 8 is a perspective view of the bottom of the 70 can. Fig. 9 is a transverse section through a can of slightly modified form.

Referring to the figures by characters of reference 1 designates a metal sheet preferably so proportioned as to form two walls of a can so that two sheets are thus necessary in the production of the four walls, as shown in Fig. 1, although it is to be understood, that if desired, all four walls of the can can be formed in a single sheet. The sheet 1 has one of its bottom corners cut away, as shown at 2 and the side edge 75 is preferably cut away obliquely as indicated at 3. The lines of the folds or bends of the sheet 1 have been indicated by dotted lines at 4 and 5, the bend 5 being located 80

near one side edge of the sheet so that, when the sheet is bent along the lines indicated, a flange 6 is thus produced along one side thereof. A rib 7 is struck from the sheet 5 1 at the bottom edge thereof along each of the lines 4 and 5, as clearly indicated in Fig. 6.

In constructing a can such as constitutes the present invention, a blank is first cut to 10 proper size and with the recessed edge portion 8. Rivet holes are then punched in the blank as indicated at 8' after which the ribs 7 are produced in the bottom edge portion of the blank. The blank is then 15 bent along the lines 10 to produce the inwardly turned portions 9. The blank is then bent along the lines 4 and 5 so that the flange 6 will lap the next adjoining wall of the can and thelapping portions of the walls 20 can be riveted together. When the blank is bent in this manner a continuous channel is formed by the inturned portions 9.

Bottom 12 of the can is preferably formed in a single piece of metal the edge portions 25 of which can be drawn downwardly to form a continuous unbroken flange 13 or said flange can be formed by welding together the ends of marginal flanges produced by cutting the blank from which the bottom is 30 made. These flanges 13 are adapted to be inserted into the channel 11 after which the ribs 7 are pinched or squeezed together so as to cause the inturned portions 9 to fit close to the flanges 13. Openings are then pinched 35 through the inturned portions 9, the flanges 13 and the lower portions of the walls of can 1 and rivets 14 inserted thereinto. Upon the completion of this operation, the bottom of the can is dipped into molten solder and 40 this solder will fill all interstices and as the channel 11 is continuous, it will be apparent that none of the molten solder will drain therefrom but, on the contrary, the solder will be retained until it becomes hard.

45 It will be seen that the continuous flange 13 on the bottom serves to tie the sheets 1 together at their laps or joints and, furthermore, the inwardly extending triangular ribs or webs 7 likewise strengthen the corners of 50 the can, as will be obvious.

In Fig. 9 a modified construction has been

illustrated. In this figure a one piece bottom 55 15 is used, the same having a depending continuous flange 16. Instead, however, of turning the lower edge portions of the sheets 17 inwardly and upwardly, a separate strip or band 18 having an inwardly and upwardly turned portion 19 is employed, this band having its ends welded together and being placed around the lower edge portions 60 of the sheets 17 so that said portions as well as the flange 16 of the bottom will extend into the channel 20 where they can be held by rivets 21. In all other respects the construction is the same as that hereinbefore 65 described.

It will be seen that the reinforcing folds or ribs in the angles or corner portions of the can are substantially flat and intersect or bisect the angles in which they are located 70 and occupy planes substantially parallel with the longitudinal axis of the can.

What is claimed is:—

1. An ice can having a solder retaining channel in its lower end along the inner sides 75 of the walls of the can, the inner wall of the channel being folded at the corners of the can to provide substantially radially disposed triangular reinforcing ribs extending up to the upper edges of said inner walls 80 whereby said channel is rendered continuous, a can bottom, and flanges depending from said bottom and seated within said continuous channel, said bottom flanges being continuous. 85

2. An ice can having its walls bent inwardly and upwardly at their lower ends, said inwardly and upwardly bent portions being folded together in the angles of the can to provide radially disposed inwardly 90 extending triangular ribs, whereby said can is reinforced at its corners and a continuous solder retaining channel is provided between the walls and the upturned portions.

In testimony that I claim the foregoing 95 as my own, I have hereto affixed my signature in the presence of two witnesses.

WILLIAM T. McCUE.
